UNITED STATES PATENT OFFICE.

GEORGE A. HOUGH, OF ONEIDA, NEW YORK.

GARMENT-FORM.

1,174,071.

Specification of Letters Patent.

Patented Mar. 7, 1916.

Application filed May 20, 1915. Serial No. 29,328.

To all whom it may concern:

Be it known that I, GEORGE A. HOUGH, a citizen of the United States, and resident of Oneida, in the county of Madison, in the State of New York, have invented new and useful Improvements in Garment-Forms, of which the following, taken in connection with the accompanying drawings, is a full, clear, and exact description.

This invention relates to certain improvements in garment forms and upon which the waist or coat portion of a garment is adapted to be mounted for display or for transference in suitable boxes, to prevent crushing or wrinkling of the garment and to give the same somewhat the shape of a wearer for whom it may be adapted, and the same is particularly applicable for the support of the waist of a burial garment for women.

The primary object is to produce a form which shall be relatively light, flexible and of inexpensive manufacture, and yet of sufficient strength and rigidity to shape the garment and retain such shape under ordinary conditions of transfer and handling, and to present the same in the most desirable condition as a display to customers or as an exhibit or sample.

Other objects and uses will appear from the following description, taken in connection with the accompanying drawings, in which—

Figure 1 is a perspective view of a garment upon the form, suitably packed for shipment, display, etc. Fig. 2 is a cross section on line 2—2, Fig. 1. Fig. 3 is a front view of the form. Fig. 4 is a view of the blank from which the front portion of the form is made. Fig. 5, 6, 7 and 8 are views of the remaining blanks constituting the form.

The blank —1—, preferably of cardboard, paper-board, or other suitable material, which constitutes the front of the form is slit inwardly along lines —2— and —3—, and —4— and —5— from its upper and lower edges, respectively, the slits —2— and —3— being substantially parallel, while the slits —4— and —5— diverge slightly as they extend inwardly. The blank is also slit inwardly from its side edges along lines —6— and —7—, respectively. The edges adjacent each of these slits are then overlapped and secured in overlapping position, thereby causing the blank to assume a curved or

dished shape, best seen in Fig. 2, and preferably, as indicated in Fig. 3, the edge —8— is lapped over the edge —9—, the edge —10— is lapped over the edge —11—, the edge —12— is lapped over the edge —13—, until the corner of edge —12— practically coincides with the corner or angular portion —14— of the blank —1—. The edge —15— is lapped over the edge —16—, the edge —17— is lapped over the edge —18—, and the edge —19— is lapped over the edge —20—, until the corner of edge —19— practically coincides with the corner or angular portion —21— of the blank —1—. This particular arrangement of overlapping edges may be reversed with equal efficiency and varied, without materially affecting the result.

The parts may be secured in overlapping position in any suitable manner, or by any suitable substance, as an adhesive.

The rear portion of the form comprises a flat blank —22— of cardboard or other suitable material, as best shown in Fig. 8, and is secured at the shoulder portions —23— and —24— to the parts —25— and —26— of the front portion —1— by means of shoulder pieces —27—, best shown in Figs. 3 and 5. These pieces are preferably of cardboard or other suitable material, and the edge —28— is secured to the rear portion and the obliquely disposed edge —29— is secured to the front portion with the edge —30— disposed upon the inner side to properly shape the shoulder portion.

The corners —31— and —32— of the back —22— are secured, respectively, to the corners —33— and —34— of the front by means of adhesive or otherwise, and preferably the width of the rear portion at the bottom is somewhat less than the width of the front portion at its bottom, so that when the respective corners of these parts are secured together the front portion is caused to bulge slightly. The body of the form is then complete with the addition of the reinforcing brace —35—, best shown in Figs. 2 and 6, and adapted to space the upper parts of the front and rear portions of the form and for this purpose the edges —36— and —37— of the reinforcing piece are deflected and secured respectively to the front and rear portions by suitable adhesive or otherwise. The waist or other garment may then be placed upon the form and for the purpose of properly supporting the collar

- thereof, a suitable shaping member —38— is provided, the blank from which the same is made being shown in Fig. 7, the same when bent in circular form adapted to be 5 positioned within and to support the collar —39— of a waist —40—, and, to prevent accidental displacement one end of the shaping member is inserted between the overlapping rear portions of the collar.
- 10 The front portion —41— rests against the front —1— of the form and against the brace —35— and is thereby held in desired position.

15 The form having the garment thereon is adapted to be placed for shipment and exhibit in a suitable box —42— and to be secured thereto by sewing or otherwise. The skirt portion of the garment may be folded and placed under the form.

20 Although I have shown one particular construction, shape and arrangement of parts and completed structure, I do not desire to limit myself to the same, as many changes may be made in the details of construction, 25 form and arrangement of the parts, and in the shape, size, etc. of the completed structure, without departing from the spirit of this invention as set forth in the appended claims.

30 What I claim is:

1. A form for garments comprising a front blank of flexible material having vertical slits at its upper and lower edges, and lateral slits at its side edges, the portions adjacent the 35 slits overlapped and secured together to form a dished front, a separate flat back, the lower corners of the dished front secured to the lower corners of the flat back, the lower edges of the front and back being 40 spaced at intermediate points, and spaced gusset shaped shoulder pieces connecting and spacing the dished front and the flat back.

Copies of this patent may be obtained for five cents each, by addressing the "Commissioner of Patents, Washington, D. C."

2. A form for garments comprising a front blank of flexible material having vertical slits at its upper and lower edges, and lateral slits at its side edges, the portions adjacent the slits overlapped and secured together to form a dished front, a separate flat back having an upper central portion 45 and downwardly sloping edge portions upon opposite sides of said central portion, the lower corners of the dished front secured to the lower corners of the flat back, the lower edges of the front and back being 50 spaced at intermediate points, and spaced gusset shaped shoulder pieces connecting and spacing the downwardly sloping edge portions of the back and the upper edge 55 of the dished front.

3. A form for garments comprising a front blank of flexible material having vertical slits at its upper and lower edges, and lateral slits at its side edges, the portions adjacent the slits overlapped and secured together to form a dished front, a separate flat back having an upper central portion 65 extending above the upper edge of the dished front, and downwardly sloping upper edge portions upon opposite sides 70 of said central portion, the lower corners of said dished front secured to the lower corners of the flat back, spaced gusset shaped shoulder pieces connecting and spacing the downwardly sloping edge portions of the 75 flat back and the upper edge portions of the dished front, and a brace disposed between and connected to the flat back and the dished front intermediate the shoulder pieces.

In witness whereof I have hereunto set my hand this 18th day of February, 1915.

GEORGE A. HOUGH.
